UNITED STATES PATENT OFFICE.

BENJAMIN BRAZELLE, OF KIRKWOOD, MISSOURI, ASSIGNOR TO HENRY A. HAMILTON,
TRUSTEE, OF ST. LOUIS, MISSOURI.

COLD-DISPENSING CAN.

1,007,060.

Specification of Letters Patent. Patented Oct. 31, 1911.

Application filed May 12, 1909. Serial No. 495,469.

To all whom it may concern:

Be it known that I, BENJAMIN BRAZELLE, a citizen of the United States, and a resident of Kirkwood, county of St. Louis, and State 5 of Missouri, have invented a certain new and useful Improvement in Cold-Dispensing Cans, of which the following is a specification.

According to the present practice of using 10 ice for cooling purposes, the blocks of ice are uncovered and the water resulting from the melting thereof either commingles with the liquid to be cooled or is wasted. In the latter case, the water runs off at a very low 15 temperature and thus fails to exercise its full cooling effect; and in the former case, it is important that the ice should be perfectly sanitary.

The principal objects of the present invention are to utilize the full cooling effect 20 of the ice, to avoid waste of materials, to expedite refrigeration of the cooling medium, to facilitate the distribution of the cooling medium in measured quantities, to 25 effect the "dry" cooling of provisions and the like, and to secure sanitary advantages.

The invention consists principally in refrigerating predetermined volumes of a suitable liquid in thin, hermetically sealed 30 containers.

It also consists in the details and features hereinafter described and claimed.

In the accompanying drawing, which forms part of this specification, and where- 35 in like symbols refer to like parts wherever they occur, Figure 1 is a perspective view of a sealed liquid-containing vessel conforming to my invention, a portion of the side being broken away to show the piece of 40 wood provided therein to overcome the effect of freezing of the liquid; and, Fig. 2 illustrates the container in the form of a cartridge for individual use.

According to my invention, suitable containers 1 are nearly filled with water or 45 solutions of suitable salts, leaving an air space in the top of the container. A piece of wood 2 is inserted in the container, which is then sealed and exposed to refrigerating 50 action, as in any of the well known pro- cesses of manufacturing ice. When the re- 55 frigeration has been carried to a sufficient extent, the containers are removed and are ready to be delivered to the consumer. The use of the air space and of the piece of wood

in the container is to permit expansion of the liquid due to freezing and thereby overcome the tendency to rupture the container. The stick of wood is longer than the width of the can or is otherwise adapted to extend a considerable distance below the surface of the liquid. For convenience in handling, the container is provided with a suitable bail or handle 3.

The most suitable form of container is a 60 wide flat-sided can of comparatively slight thickness, say about an inch and a half or two inches thick. On account of the thinness of the can, the refrigeration of its contents may be accomplished rapidly; and 65 likewise on account of the large radiating surface, its cooling effect is rapid. The wide flat sides permit the containers to be stacked with stability. When thus stacked flatwise, the total area of exposed surface of the 70 containers is reduced by the areas of the meeting sides thereof; and consequently the loss of energy during delivery may be reduced by this method of stacking and likewise the 75 rate at which the containers produce their cooling effect may be controlled by separating or stacking them as desired. As the 80 containers are hermetically sealed, there is no occasion for a separate ice chamber in the refrigerator, as the containers may be 85 placed in the same chamber as the provisions or substance to be cooled or directly in contact therewith. In order to permit 90 this last-mentioned use, it is preferable to make the containers with a sanitary surface. 95 For instance, the containers may be made of aluminum or of other suitable metal coated with tin, nickel or zinc, or with a suitable glaze that will substantially resist the at- 100 tack of the common organic acids. Such coating should protect the joints and solder as well as the body of the metal. These 105 flat containers make convenient rests or supports for provisions or vessels containing the substance to be cooled. As the liquid is hermetically sealed in the containers, there 110 is no occasion to consider sanitary conditions with respect thereto; whereas in the present practice, great precautions must be taken to insure the sanitary condition of the ice, and a fresh supply of distilled or pure water is needed for every freezing operation. It is, therefore, permissible according to my invention to use any suitable liquid solution in the sealed containers, such for

2

instance, as an aqueous solution of sulfate of soda, or of calcium chlorid, or of magnesium chlorid, or a mixture of glycerin and water. One of the principal advantages of such saline solutions is that their increase of volume due to freezing is considerably less than the increase in volume incident to the formation of ice from plain water; and consequently the tendency to rupture the containers is minimized thereby. In the case of the mixture of glycerin and water, the freezing point is below the practical refrigeration temperature, and consequently there is no risk of rupture due to the freezing of the mixture. Another advantage of the present invention is that the contents of all cans may be made uniform or in definite proportions suitable for delivery and use for household coolers; whereby all occasion for weighing is avoided. So, too, as there is no waste or leakage from the container, no humidity is introduced into the air surrounding said container.

While flat cans are preferable for household use, the container may be made in the form of sealed tubes or cartridges for individual use, as illustrated for instance in Fig. 2. When such cartridges or tubes are made elongated and of small diameter, for in-

stance about one inch or less, they are capable of individual use. For instance, when it is desired to cool a beverage, one of these cartridges is inserted in the glass or other vessel containing the beverage, and such cartridge may be removed whenever desired. For such use cartridges may be made of block tin or other metals that are too expensive for general purposes.

Obviously, my article admits of considerable modification without departing from my invention, and I do not wish to be limited to the specific construction shown and described.

What I claim as my invention and desire to secure by Letters Patent is:

As an article of manufacture, a thin flat-sided sealed metallic can nearly filled with a liquid adapted to be frozen therein and containing a stick of wood whose length is greater than the width of the can.

In testimony whereof I have signed my name to this specification in the presence of two subscribing witnesses this 10th day of May, 1909.

BENJAMIN BRAZELLE.
